UNITED STATES PATENT OFFICE.

GUSTAVE ADOLPH WEIDHASS, JR., OF NEW YORK, N. Y.

DESIGN FOR A BICYCLE-FRAME FORK.

SPECIFICATION forming part of Design No. 28,227, dated February 1, 1898.

Application filed December 20, 1897. Serial No. 662,746. Term of patent 7 years.

To all whom it may concern:

Be it known that I, GUSTAVE ADOLPH WEIDHASS, Jr., a citizen of the United States, residing at the city of New York, in the county of New York and State of New York, have invented and produced a new and original Design for Bicycle-Frame Forks, of which the following is a specification, reference being had to the accompanying drawings, which o form a part thereof.

In the drawings, Figure 1 is a perspective view of my improved bicycle-frame fork; and Fig. 2 is a transverse sectional view taken on the line 2 2, Fig. 1.

5 The leading feature of my design consists of a hollow tube which is elliptical in cross-section and has at one side a laterally-projecting approximately V-shaped hollow rib.

In the drawings forming part of this specification, A A designate the forks of the frame, which are composed of hollow tubes exteriorly elliptical in cross - section and forwardly

curved at their lower ends, as at a, each of the forks being inwardly curved at the top, as at a'. 25

Centrally upon the outer face of the forks is a longitudinal laterally-projecting rib a², which is hollow and has an exterior contour of approximately V shape in cross-section. The outer end or point of the rib is rounded, 30 as at a³.

Having fully described my invention, I claim as new and desire to secure by Letters Patent—

The design for a bicycle-frame fork, substantially as shown and described. 35

In testimony that I claim the foregoing as my invention I have signed my name, in presence of the subscribing witnesses, this 16th day of December, 1897.

GUSTAVE ADOLPH WEIDHASS, JR.
